UNITED STATES PATENT OFFICE.

PARK E. WELTON, OF AKRON, OHIO, ASSIGNEE TO MARGARET B. WELTON, OF AKRON, OHIO.

CORE FOR MANUFACTURE OF PNEUMATIC-TIRE CASINGS.

1,144,671.

Specification of Letters Patent. Patented June 28, 1915.

Application filed March 10, 1912. Serial No. 753,158.

To all whom it may concern:

Be it known that I, PARK E. WELTON, a citizen of the United States, residing at Akron, in the county of Summit and State of Ohio, have invented a certain new and useful Improvement in Cores for Manufacture of Pneumatic-Tire Casings, of which the following is a full, clear, and exact description.

10 This invention relates to the kind of collapsible cores which are chiefly used in the manufacture of the outer casings of double tube pneumatic tires.

15 The object is to provide a core which is made up of a plurality of core members capable of being quickly and accurately assembled and connected to form an annular core, and of being easily and quickly separated and removed one by one from the finished

20 tire casing.

25 The invention relates particularly to the means by which the adjacent ends of core members may be quickly and easily connected in operative relation or disconnected in such manner as to permit the core to be collapsed or disassembled by the successive inward movement—that is movement toward the center of the annular core—of the several core sections.

30 In the complete and practically refined form of the invention, as shown in the drawing, the means for separately connecting the adjacent ends of two core members consists in providing each of said members adjacent

35 to the joint between them with an inwardly directed flange, which flanges have aligned slots extending backward from their abutting ends, and in providing two connecting plates which are secured to opposite sides of

40 the flange of the core member which is first to be removed in disassembling the core, which plates overlap the adjacent flange of the abutting core member,—both plates being formed with slots which register with each other and with the slots in the two flanges, and the overhanging ends of said plates having inwardly projecting V-shaped ribs, and the overlapped flange of the core sections having V-shaped grooves to receive

50 said ribs,—which ribs and grooves are pur-

55 al with the abutting ends of said members,—and the outer surfaces of said plates being inclined away from each other toward their free ends; and in providing bolts which pass through said slots and are slideable therein, which bolts have heads on both projecting ends for engagement with said inclined surfaces.

60 The various combinations of the above mentioned parts which constitute this invention are set forth in the appended claims; and the core and its several parts, as shown in the accompanying drawings, are fully described in the following specification.

65 In the drawing, Figure 1 is a front view of a core embodying the invention when the key section thereof is in the position relative to the otherwise assembled core that it will occupy either just before it is assembled in place, or just after it has been withdrawn. 70 Fig. 2 is a sectional view of the core when the key section has been removed, the section being in the plane indicated by line 2—2 on Fig. 1. Fig. 3 is a side view partly broken away of the key member of the core; 75 and Fig. 4 is a detached view of the connecting bolt with the heads thereof removed.

80 The complete core is an annulus which is made up of a plurality of segment shaped sections. Four of these sections are employed in the construction shown, and are indicated by the reference characters A, B, C, D. Of these, the section D is the key section. That is to say, it is the section which must be last assembled in place to complete 85 the core, and must be the first section withdrawn from the core in disassembling the same. The disassembling of the annular core takes place when a tire casing is on the core. It is therefore evident that the several core sections must be removed by inward movement,—that is to say, movement toward the center of the annulus, and through the rifts in the inner periphery of the tire casing upon the core. This key member D 90 is like the other members in that it is of suitable cross sectional configuration and has an inwardly directed flange d. In so far as the present invention is concerned, the flanges are only required on the several core sec- 100

tions adjacent to the joints between sections which are connected by the means shown; but the flanges serve useful functions in the making and vulcanizing of the tire casing, 5 and therefore these flanges are made coextensive with the sections of which they are parts.

The ends of the key section are parallel and so also are the ends of sections B, B, 10 against which said ends abut when the key section is in place. In the flange *d*, of the key section, at each end thereof, is a slot *d*¹ which extends from the end of the flange backward in an approximately circumferential direction. 15 The slot does not, perhaps, show as clearly as might be in the drawing, but it is precisely like the slot *b*¹ shown in Fig. 1. In the adjacent end of the flange *b* of each of the abutting sections B, B, is a slot *b*¹ which extends from its end backward in an approximately circumferential direction, each of said slots *b*¹ being placed so 20 that they will be alined with the adjacent slot *d*¹ in the adjacent end of the flange *d* when the key section is in place.

Two connecting plates E, E are employed at each joint between the key section and the two adjacent sections B, B. These plates are secured to opposite sides of the flange *d*. 30 Each pair of plates E projects beyond the adjacent end of the flange to which they are secured, and overhang opposite sides of the adjacent end of a flange *b*. A slot *e* is formed through each pair of plates E, which 35 slot registers with and is coextensive with the slots *d*¹ and *b*¹ in the flanges *d* and *b*.

A bolt G passes through the slots *e* in both plates, and is provided with heads *g* on both ends outside of said plates. So long as these 40 heads are secured on the bolt ends said bolts cannot be withdrawn from said slots. Preferably the heads *g* screw onto opposite ends of the bolts so that they may be adjusted as required to take up wear upon their inner 45 faces or upon the outer faces of the plates E with which they coöperate.

Near the free ends of the plates E, and on the inner faces thereof are the inwardly directed V-shaped ribs *e*¹ which extend in directions parallel with the ends of section D. In the outer faces of the adjacent flanges *b* are V-shaped grooves *b*² which are parallel with the plane of division between section D and the sections, B, B. They are so placed 50 that they will receive the V-shaped ribs *e*¹ when the key section is in place. In fact, when the key section is being slipped into or withdrawn from its place in the annulus, the plates E embrace the adjacent flanges *b*, and these ribs *e*¹ enter and slide in the grooves *b*². As shown, the outer surfaces of each 55 pair of plates E are inclined away from each other toward their free ends, whereby

the distances between said outer faces gradually increases toward said free ends.

Until the key section D has reached its proper position between the ends of the adjacent sections B, the bolts G are back in the inner ends of the slots *e*. When the key member D has been properly positioned between the ends of the section B, the workman slips the bolts G along the slots *e*. These bolts will enter the slots *b*¹ in the adjacent ends of the flanges *b*; and these bolts will thereafter preserve the stated 75 alinement of the key section with the adjacent sections. By moving said bolts far enough toward the free ends of plates E the heads *g*, by engaging with the inclined outer faces of said plates will draw the plates together, (they should be flexible enough to permit this) and thereby the V-shaped ribs *e*¹ will be forced into the V-shaped grooves *b*² with the result of drawing the ends of the sections B and D into close contact.

When the key member is to be withdrawn from the core, the bolts G are moved in the opposite direction in the slots *e*, so as to be inside of the ends of the flange *d*. When, now, the freed key member is moved inward 90 toward the center of the annulus, the plates E go with it, and do not therefore interfere with such movement, as they would, if they were attached to the flanges *b* instead of to the flange *d*. Likewise the bolts remain connected with the key member so that they cannot be lost or misplaced. They are where they are wanted for use when the key member is again slipped into place to complete the core.

When the key member has been removed from the annular core, the sections B, B must be moved inward toward the center of the annulus to withdraw them from the tire casing; and any means for connecting the 105 two sections B, B with section A could be employed, provided it would permit such inward movement; but the connecting devices used at the joints between the key member and the members B can be, and 110 preferably is used for separably connecting the members B to the member A. That is to say, two plates E¹ are secured to the flange *b* of each member B, so as to overhang the adjacent part of the 115 flange *a* of the member A. These plates are provided with slots *e*. The ends of the flanges *b* between the plates are provided with registering slots *b*¹. An alined slot is formed in each end of the flange *a*, which 120 slot is substantially like the slot *b*¹ and registers with the slots *e*. The V-shaped ribs *e*¹ are formed on the inner faces of the free ends of the plates E¹, and they are arranged to engage in V-shaped grooves *a*² in the 125 flanges *a*, said grooves and ribs being par-

parallel with the plane of division between the sections B and the section A. These plates E¹ being attached to the members B which are to be moved inward as the core is being disassembled, go with said members B; and do not therefore interfere with said inward movement of said members.

Having described my invention, I claim:

1. In an annular core composed of segment-shaped sections adapted to abut endwise, the combination of inwardly directed flanges fixed to abutting sections having alined slots extending backward from the ends of said flanges, a plate fixed to the flange of one section and extending over and into contact with the flange of the abutting section, which plate has a slot which registers with the slots in the flanges, and a bolt which passes through and is slidable laterally in said slots for clamping the overhanging end of the plate to the flange which it overhangs. 65
  2. In an annular core composed of segment-shaped sections adapted to abut endwise, the combination of inwardly directed flanges fixed to abutting sections having alined slots extending backward from the ends of said flanges, a plate fixed to the flange of one section and extending over and into contact with the flange of the abutting section, which plate has a slot which registers with the slots in the flanges, and a bolt which passes through and is slidable in said slots for clamping the overhanging end of the plate to the flange which it overhangs, said last mentioned flange having a V-shaped groove which is parallel with the end of the section of which the flange is a part, and said plate having near its free end an inwardly projecting V-shaped rib adapted to enter said groove. 70
  3. In an annular core composed of segment-shaped sections adapted to abut endwise, the combination of inwardly directed flanges fixed to said sections having alined slots extending backward from the ends of said flanges, two plates fixed to the flange of one section and embracing opposite sides of the flange of the abutting section, which plates have slots which register with the slots in the flanges, and a bolt which passes through and is slidable laterally in said slots and has heads on its end for engaging with the outer surface of said plates. 75
  4. In an annular core composed of segment-shaped sections adapted to abut endwise, the combination of inwardly directed flanges fixed to said sections having alined slots extending backward from the ends of said flanges, two plates fixed to the flange of one section and embracing opposite sides of the flange of the abutting section, which plates have slots which register with the 80
- slots in the flanges, and have their external surfaces inclined and diverging toward their free ends, and a bolt which passes through and is slidable in said slots and has heads on its ends for engaging with the outer surfaces of said plates. 85
5. In an annular core composed of segment-shaped sections adapted to abut endwise, the combination of inwardly directed flanges fixed to said sections having alined slots extending backward from the ends of said flanges, two plates fixed to the flange of one section and embracing opposite sides of the flange of the abutting section, which plates have slots which register with the slots in the flanges, and have their external surfaces inclined and diverging toward their free ends, and said plates having near their free ends inwardly directed V-shaped ribs which are parallel with the end of the section, and the overhung flange on the abutting section being provided with V-shaped grooves adapted to receive said ribs. 90
  6. An annular core composed of a plurality of segment-shaped sections, of which the key section has parallel ends, said key section and the sections adjacent thereto having inwardly directed flanges in which are alined slots which extend from their ends backward, a plate secured to the flange of the key section adjacent to each end thereof and overhanging the flanges of adjacent sections, said plates having slots which register with slots in said flanges, and bolts which are slidable laterally in said slots and have heads on their opposite ends. 95
  7. An annular core composed of a plurality of segment-shaped sections, of which the key section has parallel ends, said key section and the sections adjacent thereto having inwardly directed annular flanges, a plate secured to the flange of the key section adjacent to each end thereof and overhanging and engaging the flanges of abutting sections, said plates having near their free ends inwardly directed V-shaped grooves which are parallel with the ends of the key section, and the flanges which said plates overhang being provided with V-shaped grooves adapted to respectively receive said ribs, and means for moving said plates in the direction to force said ribs into said grooves. 100
  8. An annular core composed of a plurality of segment-shaped sections, of which the key section has parallel ends, said key section and the sections adjacent thereto having inwardly directed annular flanges in which are alined slots extending from their ends backward, two plates secured to opposite sides of the flange of the key section adjacent to each end thereof and overhanging and engaging the flanges of the abutting 105

sections, said plates having slots which register with the slots in said flanges, and said plates having also near their free ends inwardly directed V-shaped grooves which are parallel with the ends of the key section, and the outer surfaces of each pair of plates being inclined so as to diverge toward their free ends, and the flanges which said plates overhang being provided with V-shaped 10 grooves adapted to respectively receive said

ribs and bolts which pass through and are slideable in said slots and have heads on their opposite ends.

In testimony whereof, I hereunto affix my signature in the presence of two witnesses. 15
